to Jeffery Dewitt Insulator Company, Kenova,
W. Va., a corporation of West Virginia

Refiled for abandoned application, Serial No.
557,186, August 14, 1931. This application De-
cember 7, 1934, Serial No. 756,538

3 Claims. (Cl. 173—318)

This invention is a suspension type insulator of the character employed in connection with high tension electrical transmission.

One of the objects of the invention is to provide an insulator which will not pull apart below its full breaking strength, even though the porcelain or other dielectric becomes cracked or damaged. A further object is to utilize thick porcelain to provide great resistance to shattering by power 10 arcs, missiles, and rough handling before erection, and the like.

The invention will be hereinafter fully set forth and particularly pointed out in the claims.

In the accompanying drawing:—

Fig. 1 is a side elevation illustrating an insulator constructed in accordance with the invention. Fig. 2 is a vertical sectional view thereof.

Referring to the drawing, A designates an insulator body constructed of porcelain or other 20 similar dielectric. As shown, said body consists of a relatively massive skirt 10, having an intermediate flat topped portion 11, from which projects a centrally disposed axially extended portion 12, preferably of approximately hemispherical 25 form. It will be noted that the axially extended portion 12 is of approximately circular cross section with its maximum diameter at its intersection with the top of the skirt 10, and terminates in a rounded extremity. By this construction, 30 the entire dielectric body is free of peripheral grooves and depressions which would normally tend to weaken the mechanical strength of the dielectric body. The intermediate flat surface 11 is provided with a plurality of recesses 13 35 equally spaced, so as to receive the correspondingly spaced legs 14, of a metal supporting cap 15. Said cap may be made of any suitable or desired metal, but cast steel is preferred. In addition to the legs 14, said cap is provided with the 40 recess 16 for engagement with the complementary head 17, of a pin 18, of an adjoining insulator unit. It will be noted that the body of the cap 15 is dome shaped, so as to fit over the upwardly 45 projecting portion 10. As shown in the drawing, the cap 15 does not conform precisely to the contour of the projection 10, and the space between the two is filled by any suitable resilient compound 19, in a manner well understood in the art.

The walls of the recesses 13 are preferably coated with any desired water proofing material well known in the art, and the legs 14 of the cap 15 are anchored in said recesses in any desired manner. It is preferred, however, to retain the legs in 50 position by means of an alloy of lead and anti-

mony, which can be applied while in a molten condition.

The pin 18 may be of any desired construction, and is inserted within a complementary recess 21 formed in the underside of the insulator body. Said pin is provided with annular shoulders 22, as shown, so that it may be firmly anchored by suitable anchoring material 23. It will be noted that the wall of the recess is also provided with annular shoulders 24, so as to retain the anchoring material in place. Any desired anchoring material may be employed, but it is preferred to use the alloy of lead and antimony above referred to. In all instances of the use of the anchoring alloy, all joints between the alloy and the dielectric are sealed against moisture which might freeze, by applying waterproofing after assembly.

An important advantage of the above described construction is that the legs 14 of the cap 15 extend downwardly, well below the inner end of the pin 18, and that the recess 21 is so deep that it extends well into the center of the projection 10, so that the inner extremity of the pin 18 is well above the plane of the intermediate surface 11, the legs and pin lying parallel but in somewhat overlapped relation. By this construction, the mechanical stresses are carried by the dielectric body in "shear and compression", rather than in "tension", as is customary in the suspension type insulator. A further advantage is that a 25 large proportion of the axial length of the insulator is covered by the metal cap, thus reducing the tendency to "cascade" a string of insulators, i. e., the arc will not jump into the hardware and 30 out again to the porcelain, as commonly occurs, but will make a curved smooth sweep from end to end of the string of insulators. It will be further noted that the legs require only small 35 holes in the massive porcelain body, thus preserving the ruggedness of the insulator as compared with cup shaped caps. The massive skirt has the great advantage of resisting shattering when touched with intensely hot arcs or struck by missiles, and it also withstands rougher handling 40 during transport and installation, and this mechanical strength is greatly enhanced by the integral axially extended portion with its maximum cross section at the intersection of the axially extended member with the top surface of the skirt 45 portion of the insulator body. A further advantage is the mechanical reliability of the structure, because the legs of the cap go far below the inner extremity of the pin. Therefore, in case of 50 a defective porcelain becoming cracked, the con-

ductor will be held up by the metal parts until the defective unit can be replaced.

This case is a substitute for application Serial Number 557,186, filed August 14, 1931.

Having thus explained the nature of the invention and described an operative manner of constructing and using the same, although without attempting to set forth all of the forms in which it may be made, or all of the forms of its use, what is claimed is:—

1. An insulator of the character described comprising a dielectric body consisting of a circular skirt portion and an integral axially disposed portion extended from the top surface of said skirt portion, said axially disposed portion being of approximately circular cross section with its maximum diameter at its intersection with said top surface, a series of spaced apart recesses being formed in said top surface and surrounding said axially extended portion, a dome-like metal cap extending over the end portion of said axially extended member and having its edge spaced from the top surface of said skirt portion, said edge having depending integral legs complementary to and extended into the respective recesses, a centrally disposed suspension pin inserted into the bottom portion of said body, the lower extremities of said legs extending to a plane well below the inner extremity of said pin, so that the mechanical stress will be carried by the dielectric material in shear and compression, and means for anchoring said legs and said suspension pin.

2. An insulator of the character described comprising a dielectric body consisting of a circular skirt portion and an integral axially disposed member extended from the top surface of said skirt portion, said top surface being provided with an annular flat surface encircling the base of said axially extended member, the maximum diameter of said axially disposed member being at its intersection with said flat surface, recesses being formed in said flat surface and arranged in spaced relation surrounding the axially extended

member, a dome-like metal cap extending over the end portion of the axially extended member and having its edge spaced from said flat surface, said edge having depending integral legs complementary to and extended into the respective recesses, an axially disposed suspension pin inserted into the bottom portion of the dielectric body, the lower extremities of said legs extending to a plane well below the plane of the inner extremity of said pin, so that the mechanical stresses will be carried by the dielectric material in shear and compression, and means for anchoring said legs and said suspension pin.

3. An insulator of the character described comprising a dielectric body consisting of a circular skirt member and an integral axially disposed member of circular cross section, said axially disposed member extending from the top surface of the skirt portion with its maximum diameter at its intersection with said top surface, a plurality of spaced apart recesses being formed in said top surface and arranged in spaced relation around said axially extended member, a dome-like metal cap enclosing the end portion of said axially extended member and provided with a skirt, the edge of which is somewhat larger in diameter than said axially extended member, said edge being spaced from the top surface of the skirt portion and provided with depending integral legs complementary to and extended into the respective recesses, said cap and said axially extended member being constructed and arranged to provide an intervening annular space of tapered cross section, a resilient composition filling said annular space, an axially disposed suspension pin inserted into the bottom portion of said body, the lower ends of said legs extending to a plane well below the plane of the upper extremity of said pin, so that the mechanical stresses will be carried by the dielectric material in shear and in compression, and means for anchoring said legs and said suspension pin.

CHARLES L. STROUP.
